SAFETY GUARD FOR LAMP TUBES

Barney Roth, Philadelphia, Pa.

Application June 24, 1954, Serial No. 438,945

2 Claims. (Cl. 240—51.11)

This invention relates to safety guards for lamp tubes and, more particularly, to a wire safety guard for use with fluorescent lamp tubes and the like to prevent the tubes from falling in the event they should become disengaged from the tube mounting brackets.

The conventional fluorescent lamp tubes are extended cylindrical members which are supported between a pair of brackets. The brackets are generally either extended downwardly from a mounting surface or extended horizontally outwardly from a vertical mounting surface. The tubes are conventionally engaged in the brackets by means of a pair of contact pins which enter a pin receiving portion of the bracket and are locked into position upon rotation of the tube. It is well known that the tubes become disengaged from these sockets or mounting brackets as a result of vibration or accidental contact or both. Generally, the final motion of the tube serving to release the contact pins from the mounting brackets results from normal building vibration and thus the tube when released falls from the brackets without warning.

It is an object of the present invention to provide a safety guard which is inexpensive to manufacture and which can be simply and easily applied to conventional tube mounting brackets for the purpose of catching the tube in the event that it should become released from the mounting brackets.

Inasmuch as there are a great number of fluorescent lamp tubes now in service, it will be evident that a simple and inexpensive type of guard which is substantially fool-proof in its operation would have a high degree of utility, and it will also be evident that such a guard must be of such a nature as to be readily applied to existing fixtures.

The accommodation of the foregoing objects and considerations is accomplished by the safety guard set forth in the following description and the accompanying drawings, in which:

Figure 1 is an elevation of a conventional fluorescent lamp tube and mounting bracket arrangement having the safety guards mounted thereon; and

Figure 2 is an enlarged perspective view showing one end of a lamp tube, its associated bracket and the safety guard.

In the figures there is shown a mounting plate 2 of conventional type within or above which is commonly positioned the ballast unit normally employed with a fluorescent lamp. Extending downwardly from the plate 2 are mounting brackets 4 and 6 which are spaced apart for a sufficient distance to provide for the admission of a lamp tube 8 therebetween. The lamp tube 8 is provided at each of its ends with a pair of pins 10 providing the conventional contact for the necessary electrical elements within the tube. The contact pins 10 also serve to support the lamp tube 8 within the mounting brackets 4 and 6 in the conventional manner.

The safety guard is preferably formed from a length of wire and has a portion 12 adjacent to one of its ends extending across the face of the mounting bracket 6

2

adjacent to the lamp tube 8. The wire is formed to provide portions 14, 16 and 18 extending around a first edge, the opposite face, and the opposite edge of the bracket. The portion 18 of the safety guard is extended as indicated at 20 and passes down under the lower surface of the lamp tube as indicated at 22 terminating in an upwardly turned end portion 24. This formation provides a cradle in the region of the wire indicated by the numerals 22 and 24 which is adapted to receive the lamp tube in the event the tube should become disengaged from the mounting brackets 4 and 6. The opposite end of the safety guard, i. e., the end of the portion 12 of the guard, terminates in a short downwardly turned end portion 26.

The portions 12 and 16 of the safety guard are preferably formed so as to lie on the same horizontal plane. While the end 26 of the wire is adapted to engage the face of the mounting bracket, the portion 12, while preferably engaging the face of the bracket, need not necessarily do so. The essential consideration is that, upon the weight of the lamp being asserted upon the cradle portion 22, 24 of the safety guard, the rotation of the portions 12 and 16 caused by the rotation of the portion 20 resulting from the downward movement of the cradle portion 22, 24 will cause the short downwardly turned end portion 26 to be pressed firmly into engagement with the inside face of the mounting bracket 6. As will be evident by viewing Figure 1 when the lamp tube descends from a normal position such as occupied by the tube 8 shown in solid lines to a lowered position as occupied by the tube 8' shown in construction lines, the two safety guards 28 and 30 will have their portions 20 and the cradle portions 22—24 rotated downwardly to the positions shown in construction lines at 28' and 30'. This rotation serves to urge the end portions 26 of the safety guards 28 and 30 into engagement with their respective mounting brackets. This force urging the downwardly turned portions 26 of the safety guards against their respective brackets serves to clamp the safety guards tightly in engagement with the brackets and prevent the portions 12, 14, 16, 18 of the safety guards from sliding downwardly over the brackets while they are supporting the lamp tube.

From the foregoing it will be evident that it is not necessary for the portions 14, 16, 18 of the safety guard to engage their adjacent surfaces of the mounting bracket for their entire length. While simplicity of construction and neatness of the final product makes it preferable that these members be formed at right angles to each other, it is only necessary that sufficient contact exist between at least a portion of the face of the mounting bracket and the portion 16 of the safety guard, and at least a portion of the opposite face of the mounting bracket and the portion 12 of the safety guard so as to provide, upon downward movement of the portion 20 of the safety guard as viewed in Figure 2, a firm engagement of the portion 26 of the safety guard with the inside face of the tube mounting bracket. It will be evident that these and other modifications may be made to the form of the invention described herein without departing from the scope of the invention as set forth in the following claims.

What is claimed is:

1. A safety guard device for a horizontally extending lamp tube mounted by and between a pair of vertically extending brackets adjacent to the ends thereof, said guard device comprising a length of wire having a lower arcuate portion and an upper loop adapted to substantially encircle one of said brackets, said loop being integrally connected to said lower arcuate portion by a straight intermediate portion, said loop being laterally offset relative to the plane containing said arcuate por-

tion, said loop having an end portion spaced from the adjacent portion of the loop, said end portion being defined by an angularly offset prong which is angularly transverse to the plane containing the loop, said arcuate portion having a free end laterally spaced from said intermediate portion in said plane containing said arcuate portions.

2. In combination, a pair of vertical brackets mounted on a horizontal support, an elongated lamp tube positioned between said brackets and having its ends releasably connected to said brackets, and guard members releasably connected to said brackets, said guard members each comprising an upper loop substantially encircling the corresponding bracket, said loop having an end portion spaced from the adjacent portion of the loop, said end portion being defined by an angularly offset prong which is angularly transverse to the plane containing said loop, an arcuate support portion transversely underlying the adjacent portion of said lamp tube, said arcuate support portion being integrally connected to said loop by an intermediate portion in such manner that said loop is laterally offset relative to the plane contain-

5

ing said arcuate support portion, said arcuate support portion normally being free of the weight of the tube to hold said prong out of biting, frictional engagement with the adjacent surface of the corresponding bracket, and said arcuate support portion being actuatable by the weight of said tube to rock said loop to rotate said prong into biting frictional engagement with the said adjacent surface of the corresponding bracket.
